UNITED STATES PATENT OFFICE.

GUSTAV ENGISCH, OF BERLIN, GERMANY.

TOY AIRSHIP.

949,420.

Specification of Letters Patent. Patented Feb. 15, 1910.

Application filed December 31, 1908. Serial No. 470,135.

To all whom it may concern:

Be it known that I, GUSTAV ENGISCH, a citizen of the German Empire, residing at Berlin, Prussia, Germany, have invented 5 certain new and useful Improvements in Toy Airships, of which the following is a specification.

My invention relates to improvements in toy air ships. And the object of the improvements is to provide a buoyant toy air ship which can be driven and steered in a simple way.

The invention will be readily understood from the following specification and the accompanying drawing, in which—

Figure 1, is a rear view of the air ship, Fig. 2, is a side view, and Fig. 3, a plan of the same.

The same letters of reference have been 20 used in all the views to indicate corresponding parts.

Referring to the drawing, *a* indicates a buoyant body which is preferably made of rubber. The said buoyant body has the 25 usual cigar-like form, and it can be inflated by a suitable gas the specific gravity of which is less than that of the air. From the body a car *m* and a frame *b* are suspended. At its front end the frame *b* is formed with 30 a bore for a propeller shaft *e* carrying at its end a propeller *d*. To the rear end of the frame there is secured a connecting means, for example a hook *f*. Through the latter and through a hook provided at the rear end 35 of the propeller shaft a rubber band *g* is looped two or three times. To the rear end of the frame *b* a vertical shaft *h* is linked which carries a rudder *i* consisting of a frame covered with paper or fabric. The 40 shaft is held against rotation by friction, so that it remains in its position when adjusted for performing a flight. The frame also carries horizontal planes *n*, which can be turned in bearings of the frame when the 45 air ship is to be raised or lowered. Also the planes *n* are adjusted for each trip of the ship, and they remain in their adjusted position to the end of the flight.

The frame *b* of the car is secured to the 50 buoyant body by rigid connecting means. Therefore the car is not suspended within a special balloon netting. Preferably the said rigid connection consists of one or more elas-

tic rods *k* which are looped in the manner shown in Fig. 1. The depending portions 55 of each rod are intersecting each other; at their point of intersection they are interconnected, as indicated with 1 in Fig. 1. The ends of the rods are secured to the frame of the car. By providing looped rods as described the same rods may be used for balloons of different sizes. The buoyant body is pressed into the loop sufficiently to produce a rigid connection of the latter with the frame. They can be longitudinally 60 shifted on the said body. The connecting rods *k*, the frame *b* and the car *m* are preferably made of very light material, such for example as bamboo, so that the air ship is 65 buoyant without requiring a balloon of excessive size.

Instead of the driving and steering means referred to other suitable means may be provided.

In order to drive the air ship the propeller 75 *d* is rotated about its axis, so that the rubber cord *g* is put under tension. When the propeller is released it is rotated in the opposite direction by the rubber cord, whereby the air ship is driven.

The air ship is steered by the rudder *i* and the planes *n*, which are adjusted before starting the same. The rudder and the planes are held in their adjusted positions 80 by friction.

I claim:

1. A free flying toy air-ship comprising in combination a buoyant body, a frame, driving means, steering means, and a plurality 90 of rods attached to said frame, and embracing portions of said body, the two halves of each rod intersecting each other between said body and said frame.

2. A free flying toy air-ship comprising in combination a buoyant body, a frame, driving means, steering means, a plurality of rods attached to said frame and embracing portions of said body, the two halves of each rod intersecting each other between said body and said frame and being interconnected 100 at their point of intersection.

GUSTAV ENGISCH.
